(57) **CLAIM**

The ornamental design for a school bus stop sign, as shown and described.

DESCRIPTION

FIG. 1 is a front view showing of a school bus stop sign; FIG. 2 is a second, exemplary, front view thereof; and, FIG. 3 is a back view thereof.

The broken line showing of a bus is included for the purpose of illustrating portions of the "article" and forms no part of the claimed design.

The invention is an updated design for a school bus stop sign. The design incorporates the figure of a police officer holding a stop sign. Although shown in black and white in the drawing included in this application, it is envisioned that the design could be done in various colors to be more noticeable to motorists.
